HENRI LUGLIEN MARIE JOSEPH BÉNARD, OF PARIS, FRANCE, ASSIGNOR TO ANCIENS ETABLISSEMENTS BARBIER, BÉNARD & TURENNE, SOCIÉTÉ ANONYME, OF PARIS, FRANCE, A JOINT-STOCK COMPANY OF FRANCE

SHADOWLESS LIGHTING APPARATUS

Application filed April 19, 1928, Serial No. 271,277, and in France February 10, 1928.

The present invention relates to certain improvements applicable to lighting apparatus which do not throw shadows, and are more particularly intended to lighting up operating benches or the like.

These lighting apparatus broadly comprise, as is well known, one or more central luminous sources about which is located the reflecting system which reflects the luminous rays emanating from the luminous source on to a given portion of the operating bench at different angles, whilst an optical system, constituted by optical lenses or by combination of mirrors and reflectors indifferently, is preferably inserted between the luminous source or sources and the above mentioned reflecting system.

A first improvement with which the present invention is concerned is intended to render these lighting apparatus more secure and such improvement essentially consists in fitting up a shadowless lighting apparatus with an emergency lighting device constituted by one or more luminous sources completely independent of the principal luminous source or sources. When these auxiliary lighting sources are electrical, they are mounted in a shunt circuit of the circuit of the main sources in order to render them independent. More advantageously, the auxiliary sources may be mounted on a totally separate circuit fed for example by a battery of accumulators.

The emergency lighting sources will be preferably arranged in such wise that the light they emit shall be reflected back at different angles on to the surface to be lit up, said emergency lighting source thus itself providing to a certain extent shadowless illumination. The object of this emergency source of illumination when it operates in conjunction with the principal lighting system, will likewise be to project light on the portions fringing the operating bench, which are normally not lit up.

Another improvement forming the object of the present invention aims at obviating another drawback obtaining with devices of this nature as at present known and which resides in the fact that they give off great heat which

may seriously inconvenience the surgeons. This heat is given off by the infra-red rays emitted by the principal luminous source or sources. This improvement consists in combining with a lighting apparatus that does not throw shadows, a device inserted in the path of the luminous rays between the luminous emitting source or sources and the surface to be lit up, such device being capable of absorbing the heat carried by said rays.

According to a form of construction, the heat absorbing device is constituted by heat absorbing glass which absorbs the infra-red heat rays, such glass assuming the form of a sleeve of suitable thickness surrounding the luminous source, an annular space being left between the luminous source and the sleeve, through which a sufficiently strong current of air is passed to get rid of the heat.

Said heat absorbing glass might be applied, with the same end in view, to the construction of the silvered reflecting surfaces as at present used, the infra-red heat rays being then arrested during their double passage through the glass.

In this case, the reflecting surfaces are cooled by placing them in contact with a sheet of copper provided with fins or in contact with a substance having a great latent heat of fusion.

In the accompanying drawings, forms of construction of the various improvements in accordance with the invention have been illustrated diagrammatically and merely by way of example.

In these drawings:

Fig. 1 is a longitudinal sectional elevation of a lighting apparatus which does not throw shadows, of known type, and fitted up with an emergency lighting system in conformance with the invention.

Fig. 1^a shows the feeding circuits of the principal and emergency lighting apparatus respectively.

Fig. 2 shows a form of construction of the device for absorbing the heat.

Fig. 3 shows an alternative form of Fig. 2 and

Fig. 4 another alternative.

The shadowless lighting device illustrated

in Fig. 1, essentially comprises, in the known manner, a central luminous source 1 about which an optical system is arranged, for example a Fresnel annular lens 2 which throws the luminous rays emitted by the source 1 on to a reflector 3 either conical or having a plurality of facets, in a horizontal or practically horizontal sheet. In its turn, the reflector 3 reflects the luminous rays, concentrating them at the same time, on to a comparatively small surface of the operating bench 4. This surface is consequently lit up without shadows.

This is a known type of shadowless lighting device, but it should be noted that the improvements which will be described hereinafter are not solely adaptable to this type of device, but are on the contrary adaptable to all devices of the same type whatever may be the particular construction either of their central luminous source or of the intermediate optical device and the outer reflecting system.

According to the invention, the illuminating apparatus is fitted up with an emergency lighting system preferably constituted by a plurality of luminous sources such as 5 whose circuit is so formed that said electric lamps 5 shall be completely independent of the principal source 1. To this end, their circuit may be shunted across the circuit of the source 1. It will be more advantageous to render the circuit of the lamps 5 completely separate from that of the lamp 1 and it may be fed, for example, through a battery of accumulators. Under these conditions, whatever may be the cause of the stoppage of the source 1, the auxiliary lamps 5 will give the requisite emergency illumination. This arrangement obviates the drawback obtaining with the devices known hitherto with which operations were sometimes interrupted on account of a breakdown in the lighting of the principal source 1. With the above mentioned device, when the source 1 fails, the lamps 5 will give sufficient light to enable the surgeons to continue operating. The lamps 5 will moreover be so located that they provide by themselves light to a certain extent without shadows.

Again, it should be noted that said lamps 5, when they are used in conjunction with the luminous source 1, light up to advantage the portions fringing the operating bench which are normally not lit up by the principal luminous source 1.

In certain cases, it may be of advantage to mount an automatic circuit breaker in the circuit of the luminous sources 5 so as to close the lamp circuit as soon as the principal luminous source 1 fails, said circuit breaker on the contrary breaking the circuit of the lamps 5 when the lamp 1 is in working order.

Various forms of construction of another improvement with which the invention is concerned which enables the heat given off by the principal luminous source or sources 1 to be

absorbed, has been illustrated in Figs. 2 to 4.

The heat given off by the luminous source 1 may likewise be absorbed by means of glass composed of silica, sodium oxide, calcium oxide, arsenious oxide and iron oxide and which absorbs the infra-red heat rays emitted by the source 1. 70

In the case illustrated in Fig. 2, a cylindrical sleeve 8 made of glass of this composition is inserted between the Fresnel annular lens 2 and the source 1. The luminous rays emitted by the source 1 are obliged to pass through said sleeve which cuts off the heat rays. In order to prevent the sleeve 8 from heating up, a fairly strong current of air is passed through the space provided between the sleeve 8 and the luminous source 1 whereby the heat absorbed is conducted away. 75

In order to absorb the heat, the device illustrated in Fig. 3, in which the reflector 3, which may be a solid of revolution or have multiple facets, is constituted by glass based on oxide of iron, may likewise be adopted. As usual, said reflectors are silvered on the outside. The luminous rays which fall on the reflector are thus obliged to pass twice through the glass of special composition, so that the infra-red rays are cut off thereby. The reflector may be cooled by placing it in contact on the outside with a sheet of copper provided with cooling fins or with any other substance possessing a great latent heat of fusion. 80

Finally, as illustrated in Fig. 4, the above mentioned glass of special composition may take the form of a disc 9 closing the lower part of the cupola formed by the reflector 3. In this instance likewise, the luminous rays are obliged to pass through the glass and the heat rays are consequently arrested. Moreover, the glass might be arranged in any other manner, it being essential that the rays emitted by the luminous source 1 be obliged to pass through it. 90

It will be readily realized that with any one of these devices, the luminous rays which are concentrated on the operating bench do not carry heat with them and that they are consequently not liable to inconvenience the surgeons even after a considerable length of time. 100

As has been already said, it is evident that the improvements described above as applied to a special type of shadowless lighting device, are applicable without being modified or only with unimportant modifications of detail, to all shadowless lighting devices whatever their particular construction may be. 110

It is moreover self evident that the invention has only been described and illustrated here in a purely explanatory but by no means limitative manner, and that it could be subjected to various modifications of detail without departing from the spirit thereof. 120

I claim:

1. In a lighting device, the combination with a principal light source, an optical condensing means adapted to condense light rays emitted by said source, and a system of reflecting mirrors adapted to reflect said rays on to a surface so situated relative to said principal lighting source as to receive shadowless illumination, of emergency light sources completely independent of said principal source and so disposed with respect to said reflecting mirrors as to contribute substantially shadowless illumination to said surface.
- 15 2. In a lighting device, the combination with a principal electrical light source, an optical condensing means adapted to condense light rays emitted by said source, and a system of reflecting mirrors adapted to reflect said rays on to a surface so situated relative to said principal lighting source as to receive shadowless illumination, of emergency electrical light sources completely independent of said principal source and so disposed with respect to said reflecting mirrors as to contribute substantially shadowless illumination to said surface, and independent electric feeding circuits for said principal and auxiliary sources respectively.
- 30 3. In a lighting device, the combination of a lighting source, an annular Fresnel lens disposed about said source, a system of reflecting mirrors surrounding said Fresnel lens and adapted to reflect the light rays on to a surface so situated relative to said lighting source as to receive shadowless illumination, and a cylindrical sleeve inserted between said light source and said annular lens, said sleeve being made of heat absorbing glass adapted to cut off the infra-red heat rays emitted by said source.
- 35 4. In a lighting device, the combination of a lighting source, an annular Fresnel lens disposed about said source, a reflecting system surrounding said Fresnel lens and so disposed as to produce shadowless illumination on a given surface, and a cylindrical sleeve inserted between said source and said Fresnel lens and made of heat absorbing glass adapted to cut off the infra-red heat rays emitted by said source.

HENRI LUGLIEN MARIE JOSEPH BÉNARD.
